ABSTRACT: A buckle for ski and/or mountaineering shoes wherein the clamping loop is releasably secured to a mounting plate fixedly secured to the shoe by a screw.

BUCKLE FOR SKI AND MOUNTAINEERING SHOES

The invention relates to a buckle for ski and mountaineering shoes consisting of a clamping loop cooperating with a toothed tensioning lever, said clamping loop being pivotally supported about a horizontal axis on a mounting plate.

In known buckles of this type, the clamping loop is rigidly, that is unreleasably, connected to the mounting plate. This has the considerable disadvantage that in the case of a breaking or a damage of the clamping loop, the entire unit consisting of the clamping loop and the mounting plate must be removed from the shoe and replaced by a new unit. In order to release the mounting plate from the shoe, the retaining rivets have to be removed by means of a drilling machine. Further, a riveting machine is required to secure the new unit which consists of the clamping loop and mounting plate to the shoe. Thus, the type of construction used so far has the disadvantage that the replacement of a clamping loop together with the mounting plate is difficult, is time consuming and requires special tools and that, in case of a breaking or damage to the clamping loop, the entire unit consisting of clamping loop and mounting plate must be replaced with a new one.

In order to overcome these disadvantages, according to the invention, the annular clamping loop is pivotably arranged in a bearing portion which is releasably connected to the mounting plate by a low-head screw. This new type of construction has the advantage that the user of the ski or mountaineering shoe can himself replace the broken or damaged clamping loop with a new clamping loop with only a few manipulations and without any special tools.

The invention will be described hereinafter in more detail in connection with one advantageous exemplary embodiment which is illustrated in the drawing in which:

FIG. 1 is a longitudinal cross-sectional view of a buckle mounted to a partially illustrated ski or mountaineering shoe;

FIG. 2 is a top view of the clamping loop and mounting plate of said buckle in an enlarged scale;

FIG. 3 is a longitudinal cross-sectional view along the line III-III of FIG. 2; and

FIG. 4 is a top view of the mounting plate.

The illustrated buckle consists substantially of a toothed tensioning lever 3 pivotally supported about the axis of a pin 2 in a bearing block 1 and of a clamping loop 5 which is engageable with the notches 4 of said tensioning lever. The clamping loop is pivotably supported about the horizontal axis 8 on a mounting plate 7. The mounting plate 7 is secured to the instep portion 6 of the shoe. The bearing block 1 of the tensioning lever is mounted to the other instep portion 10 of the shoe with a mounting plate 9.

As illustrated in the drawing, the annular clamping loop 5 is pivotably arranged in a bearing part 11 which is releasably connected to the mounting plate 7 in the illustrated embodiment by means of a low-head screw 12. In the illustrated, particularly advantageous embodiment, the mounting plate 7 has a vertical cylindrical stub 14 which is provided with an internal thread 13 and which is used for both a pivotal support of the bearing portion 11 about a vertical axis 15 and also for threadably receiving the low-head screw 12. The bearing portion 11 is thereby advantageously formed of a piece of sheet metal to define a pivot bearing for the hinge part 5a of the clamping loop. The bearing portion 11 is preferably approximately cylindrical and is pivotably supported about the stub 14 by the tongues 11b. This new type of structure has the advantage that the pressures exerted by the clamping loop 5 are exerted against the stub 14 of the mounting plate so that the screw 12 is not loaded. Furthermore, this type of structure has the advantage that the clamping loop 5 is not only pivotable about the horizontal axis 8 but also about the vertical axis 15 so that the handling of the clamping loop during closing of the buckle with the tensioning lever 3 is made easier.

A nearly semicircularly shaped ridge 16 is further advantageously provided on the mounting plate, which ridge partially surrounds the bearing portion 11b and the edges 17, 75

18 define stops for limiting the swinging movement of the clamping loop 5. The clamping loop can move only through a small angular zone during deviation in the direction of arrow A about the vertical axis 15 or the stub 14 until the bearing portion 11a touches either one of the stops 17, 18. The ridge 16 can, if desired, be formed by a corresponding forming of the mounting plate 7 made of sheet metal. However, in the illustrated advantageous embodiment, this ridge is arranged on a cover plate 19 which is rigidly connected to the mounting plate 7. In the illustrated simple embodiment, the cover plate 19 has rivet stubs 20 which are inserted from above through correspondingly large holes 21 of the mounting plate 7 and are then riveted according to FIG. 3 so that a rigid and unreleasable connection between the two plates 7 and 19 is created. These rivet stubs 20 are further used for the passage of the retaining rivet 22 through the holes 23 of said rivet stubs to secure the mounting plate to the instep portion 6 of the shoe.

The clamping loop 5 can consist of a simple annular clamp which is formed from wire. In the illustrated advantageous embodiment, however, the clamping loop 5 is constructed as a spring clamp. The hinge part 5a of the clamping loop is for this purpose rigidly connected to telescoping pipes 5b wherein springs which are provided on the ends of the part 5c of the clamping loop are arranged and are secured to the free ends of the pipes 5b. Thus, in case of an inclined stress on the clamping loop 5, the part 5c of the clamping loop can move in direction of the pull B against the spring pressure. This results in the advantage that the closing of the tensioning lever 3 is made easier and that also less stress is placed on the mounting plate or the stub 14.

In the embodiment illustrated in FIG. 1, the bearing block 1 is advantageously arranged on a baseplate 1a which is releasably connected to the mounting plate 9 so that in the case of a breaking of the tensioning lever, the bearing block 1 can be replaced quickly and easily.

The embodiments of the invention in which I claim an exclusive property or privilege are defined as follows:

1. A buckle for ski and mountaineering shoes having annular clamping loop means fixed to one instep portion of said shoe and toothed tensioning lever means fixed to the other instep portion of said shoe, said annular clamping loop means comprising:

45 a mounting plate secured to said one instep portion of said shoe, said mounting plate having a cylindrical stub portion projecting vertically therefrom, said cylindrical stub portion having an internally threaded opening therethrough; means secured to said annular clamping loop means defining a tongue extending away from said clamping loop and being pivotally connected to said cylindrical stub; and a low-head screw threadedly engaged with said internally threaded opening in said cylindrical stub to thereby releasably secure said tongue means to said cylindrical stub, the head of said screw engaging the vertical edge of said cylindrical stub to effect a pivotal connection of said tongue means to said mounting plate which is free of a binding, frictional.

55 2. Buckle according to claim 1, characterized in that the mounting plate has a nearly semicircularly shaped ridge which partially surrounds the bearing portion and is used as a stop to limit the swinging movement.

60 3. Buckle according to claim 2 characterized in that the ridge is arranged on a cover plate which is rigidly connected to the mounting plate.

65 4. Buckle according to claim 3, characterized in that the cover plate has hollow rivet stubs which secure the cover plate to mounting plate and permit the passage of the retaining rivet therethrough.

70 5. Buckle according to claim 1, characterized in that the clamping loop is constructed as a spring clamp.

6. Buckle according to claim 1, wherein said tongue means has means defining an opening therethrough for receiving said cylindrical stub, said cylindrical stub projecting above said

tongue means so that the engagement of said head of said screw with said vertical edge of said cylindrical stub will prevent said head of said screw from interferring with the pivoting motion of said tongue means.

7. A buckle for ski and mountaineering shoes, comprising: 5
 toothed tensioning lever means fixed to one of the instep portions of said shoe;
 annular clamping loop means having an annular clamping loop cooperating with said toothed tensioning lever means, said annular clamping loop having a mounting 10 plate secured to the other of the instep portions of said

shoe, said mounting plate having means defining a pivot shaft thereon; means secured to said annular clamping loop defining a tongue extending away from said annular clamping loop; and means for releasably and freely pivotally securing said tongue means to said shaft to effect a pivotal connection which is free from a binding frictional engagement between said tongue means, said mounting plate and said shoe.
